UNITED STATES PATENT OFFICE

2,020,517

TREATMENT OF FIBROUS AND TEXTILE MATERIALS

Bruno Rewald, Hamburg, Germany, assignor, by
mesne assignments, to American Lecithin Com-
pany, Cleveland, Ohio, a corporation of Ohio

No Drawing. Application October 5, 1932, Serial
No. 636,422. In Germany January 11, 1930

10 Claims. (Cl. 8—6)

This application is in part a continuation of
my copending application Ser. No. 459,842, filed
June 7, 1930.

The present invention concerns the treatment
5 of fibrous textile materials of all kinds both in
the loose form and when woven into fabrics and
the like.

It has been found that the addition of phos-
10 phatides, more particularly of vegetable lecithin
such as may be obtained in considerable quan-
tities from soya bean, peas, lupins, grain germs,
yeast and numerous other materials, produces
particular advantages in the handling and treat-
15 ment of textile fibres, threads and fabrics of all
kinds. The treatment may be employed with
textiles of all kinds, such as cotton, wool, arti-
ficial silk, silk and the like and may be embodied
with advantage during any of the various stages
20 in the production of the finished yarn or of the
finished fabrics.

For example it has been found that the addi-
25 tion of lecithin during dyeing, either to the dye
liquor or one or another of the necessary baths,
wetting out bath, mordant bath, etc., gives a
greater brilliancy to the dyed material, a softer
feel to the material and better dyeing through
30 of hard threads and thick fabrics. Further the
fibres are protected against the adverse influence
of the liquor. It may be noted, that dye liquors
and other liquors ordinarily used in conjunction
35 therewith, all contain water as the largest con-
stituent. A great resistance of the colored fab-
ric to rubbing is obtained, with the dyed fibrous
material simultaneously with a high gloss. These
properties are also visible in a high degree in
40 the materials produced therefrom.

Further, the addition of lecithin may also be
45 made to the boiling materials which are alkaline
aqueous liquids with which the raw cotton is
boiled under pressure, and the bucking is done
in a dilute acid solution. It was observed that
by this addition a better effect resulted in spite
of a shortened period of steeping.

Also, it is possible to employ the lecithin in
50 the cleaning and brightening of the fibrous ma-
terial for which purposes it is added to the clean-
ing or brightening baths, whether these are
aqueous solutions, soaps, alkalies etc. or organic
liquors, light gasoline, carbon tetrachloride etc.

In this manner the cleaning action is increased
and the feel and appearance of the brightened
material improved.

The lecithin suitable for this purpose can be
obtained in known manner by extraction with 5
suitable solvent materials, e. g. benzol-alcohol
mixture, benzol-methyl-alcohol etc. from vege-
table raw materials such as for example soya
beans, lupins, cereal germs and yeast. If neces-
sary for the purpose for which it is intended, it 10
can be purified and freed from excess of oil. For
the present purpose, in particular, lecithins may
be employed which are unsuitable for nutrient
and medical purposes. Instead of lecithin, the
phosphorus-containing residues of high emulsi- 15
fication capacity, such as those obtained as res-
idues in the purification of phosphatides for
nutrient purposes can be used.

These phosphorus-containing residues are ob-
tained by the extraction of soy-bean oil with or 20
organic solvents.

In the extracted oil, mucilaginous matters f. i.
consisting of lecithin and impurities are sus-
pended. This suspension is removed from the 25
oil by deposition after leaving the oil to rest for
a longer period or by centrifuging the oil. The
obtained residues consist of about 30-70% of
water, 30-70% of oil and 30-70% of phosphorus-
containing substances. 30

For the production of these suitable vegetable 35
lecithins the procedure may be that the husked
soya beans are broken up by rolling and extracted
with a mixture of 90 parts of benzol and 10 parts
of alcohol at a temperature of 20 to 30° C. The
extracted material contains besides impurities, 40
the extracted oil and the lecithin. After driving
off the extracting agent from the solution by
evaporation, the lecithin is separated from the
oil by leading in waste steam, it is separated 45
from the main bulk of oil by centrifuging and
is thereupon dried by heating under reduced air
pressure, i. e. in a partial vacuum.

In this manner there may be obtained a vege-
table lecithin which contains approximately 30 45
parts of oil and approximately 70 parts of lecithin,
which swells in water, and is adapted for uniform
distribution into the solutions which are used for
the treatment of the fibres and of the materials
prepared therefrom. 50

Furthermore, a suitable vegetable lecithin can also be obtained from soya beans by extracting the crushed soya beans at approximately 60° C. with benzene. The solution obtained in this manner is freed from the solvent by evaporation and treatment with steam. From the oily residue remaining, the vegetable lecithin containing 30-40% of oil, as well as impurities and water gradually settle out in the bottom. This mass is collected and dissolved in trichlorethylene and freed by filtration from the solid residues, separated from the water and the solvent further evaporated. If the purified vegetable lecithin so obtained, contains too large a quantity of oil, this latter may be partly or wholly removed by treatment with acetone or acetic ester.

This lecithin is used in the same manner as that produced as described earlier.

The following examples are given purely by way of illustration. The parts are by weight.

Example 1

To 1000 parts of an aqueous mordanting bath, such as stannous chloride solution, ferrous chloride solution etc. add about 2 to 4 parts of lecithin, and mordant the cotton in the usual or any approved manner, and dye in the usual manner.

Example 2

30 The same amounts of lecithin can be added to one or both of the hot solutions of tannic acid and tartar emetic used for mordanting cotton (white mordant) to be dyed with basic dyes.

Example 3

To 1000 parts of the dye bath to be used with the cotton treated by the operation of Example 2 e. g. malachite green, methylene blue, rhodamine, auramine, Bismark brown or fuchsine, there may be added about 1 to 2 parts of lecithin. The steps of the dyeing operation may be carried out in the conventional manner. Acid dyeing baths should not be used.

Example 4

45 To 1000 parts of a dye bath containing a direct dyestuff, e. g. Ciba-sky-blue F. F., pink 2 B, green G N concentrated, Red 3 B or other direct dye for cotton, or a mixture of these, the dye being about 50 1 to 3% of the weight of the cotton, is added about 0.5 to 3 parts of lecithin. The cotton previously wetted out, if desired, is introduced and dyed in the conventional manner.

Example 5

To 1000 lbs. of a dye bath for sulphur dyeing, containing say 48 lbs. of soda ash, 22 lbs. of actual Na₂S with or without turkey red oil, about 60 17 lbs., and 64 lbs. sulphur yellow G, or any other sulphur dye or mixture of them, there is added 0.5 to 5 lbs. of crude phosphatides.

65 Heavy cotton cloth to be dyed, say 2.54 sq. yds. of the cloth weighing a pound, is introduced and run through the bath continuously, at high speed, the bath being kept boiling hot or at the desired temperature the cloth being in the bath about 2 minutes. It then runs out, through Na₂Cr₂O₇ and acetic acid or other oxidizing solution, is washed, squeezed and dried.

70 The lecithin or other phosphatide can be added to other dye baths containing any kind of dyestuff.

Example 6

75 Cotton fabric is put into a kier as usual. Caus-

tic soda and soda ash solution, having an alkalinity of 10-11% NaOH, and containing say 0.3% of lecithin, is run in. The cover put on and the liquor circulated, hot, for 14-16 hours, at say 5 lbs. pressure. The treated cotton fabric is of a characteristic and brilliant appearance which may not be obtained by the known processes.

Example 7

Cotton is bucked in 5 Tw. sodium hypochlorite 10 solution, with enough H₂SO₄ or HCl to make the bath very feebly acid. The bucking solution may contain about 0.5 to 3% of lecithin.

Example 8

15

Cold bleach. The cotton fabric is singed, then passed through (a) a solution of malt extract containing 3.5 gallons of diastatic malt extract in 40 gallons of water. Then it is let stand for 40-50 minutes. Then it is run through a 6-box 20 open soaper. In the first two boxes (b and c) of this soaper, is provided running water, the second one preferably hot water. The next four boxes (d, e, f, g) contain boiling hot 10-11% NaOH 25 solution. After the fabric comes out it is allowed to stand one-half hour. The material cools off during this time. Then it is taken through another 6-box open soaper, the first box (h) contains hot water, the second box (i) contains 30 cold water. The next box (j) contains a solution of sodium hypochlorite, cold, at 4-5° Tw. The fourth (k) box contains HCl of 2° Tw. The fifth box (l) contains HCl of 2° Tw. The sixth box (m) contains hot water. It is then 35 squeezed and dried on hot cans.

Example 9

Wetting out. The water used for wetting out cotton, wool, silk, artificial silk or other fabric or 40 yarns, etc. may have 0.1-1% of lecithin added. This increases penetration, thus shortens the time needed for wetting out, gives more level dyeing and a softer feel.

Example 10

45

In voils, marquisettes, etc., for dress goods, lace curtains, etc. it is usual to boil in a kier, then sour, bleach, wash, soap-dye-and-starch or soap-blue-and-starch. By adding about 2% of lecithin 50 to the soap dye or blue and starch or dextrine solution used in the last step before final drying, an improved finish can be secured.

In all of the above examples, where I have referred to adding a given amount of lecithin to an 55 aqueous bath, in which lecithin is of course well known to be insoluble, I may conveniently first emulsify the desired amount of lecithin with say 5 to 20 times its weight of water, soap solution, starch solution, mild soda solution, or other liquid which is to become a part of the final bath, and then homogenize such emulsion by passage through a homogenizer, e. g. a colloid mill and add such emulsion to the other constituents of the bath, the other constituents of the final bath 65 having first been dissolved in the remaining portion of the water. The bath is, of course, well mixed. Or, if desired, I may make up the final bath, all except the lecithin, emulsify the lecithin with a small part of the said bath, and add the 70 emulsion, after homogenization if desired, to the remainder of the bath, and mix well.

According to this invention a progressive and new technical effect is obtained. The fabrics treated with phosphatides according to the in- 75

vention show a soft and favourable feel and show a higher brilliancy than the known products.

I claim:

- 5 1. In the treatment of cellulosic fibrous textile materials and of fabrics manufactured therefrom with treating liquors in which water constitutes the largest constituent the addition of vegetable lecithin to the said liquors and the treatment of said fibrous materials therewith.
- 10 2. A process for the treatment of fibrous textile material in which a chemical treatment of said material is effected with a heated alkaline liquid containing added vegetable lecithin.
- 15 3. A process for the treatment of fibrous textile material, and of fabrics manufactured therefrom, in which an addition of vegetable lecithin is made to a dye liquor, with which said textile material is treated.
- 20 4. In the treatment of cellulosic textile materials, the herein described improvement which comprises subjecting the said textiles to treatment with a bath containing added vegetable phosphatides, the largest constituent of said bath being water.
- 25 5. Chemically treated textile material containing a small amount of vegetable phosphatide, the said phosphatide reducing the amount of injury to the textile material during the chemical treatment used.
- 30 6. Dyed textile material containing a small

amount of vegetable phosphatide, the said phosphatide acting to prevent injury to the said textile materials during dyeing process and acting to cause the dye to penetrate thick hard threads and produce a complete dyeing through of the 5 textile material.

7. A process for the treatment of fibrous textile material, and of fabrics manufactured therefrom, in which during a dyeing process performed upon said textile an addition of vegetable lecithin 10 to the dye liquor is made in such a proportion only as to give a dye bath in which the said textile material is dyed.

8. In the treatment of textile materials, the herein described improvement which comprises 15 subjecting the said textiles to treatment with a hot bath containing added vegetable phosphatide and free from added materials which are easily fermentable.

9. In the treatment of fibrous textile materials 20 with an aqueous bath, the herein described step of adding a vegetable phosphatide, as its sole added emulsifying agent, to said bath, the largest constituent of said bath being water.

10. In the treatment of textile materials, the 25 herein described process which comprises treating the said textile materials with cleaning and brightening liquids containing a vegetable phosphatide.

BRUNO REWALD. 30
